UNITED STATES PATENT OFFICE.

ELMER E. TEMPLE, OF COLUMBUS, OHIO.

DESIGN FOR A NAME PLATE FOR USE ON AUTOMOBILES.

Application filed June 19, 1922. Serial No. 2,732. Term of patent 3½ years.

To all whom it may concern:

Be it known that I, ELMER E. TEMPLE, a citizen of the United States of America, residing at Columbus, in the county of Franklin and State of Ohio, have invented a new, original, and ornamental Design for a Name Plate for Use on Automobiles, of which the following is a specification, reference being had to the accompanying drawing, forming part thereof.

I claim:

The ornamental design for a name plate for use on automobiles, as shown.

In testimony whereof I have affixed my signature.

ELMER E. TEMPLE.
